United States Patent Office.

FREDRICK J. SMITH, OF CHICAGO, ILLINOIS.

Design No. 4,833, dated April 18, 1871.

DESIGN FOR A PUBLIC URINAL AND WATER-CLOSET.

The Schedule referred to in these Letters Patent and making part of the same.

To whom it may concern:

Be it known that I, FREDRICK J. SMITH, of Chicago, in the county of Cook and State of Illinois, have invented a new and useful Improvement in a Combined Urinary and Water-Closet; and I do declare that the following is a true and accurate description thereof, reference being had to the accompanying drawing and to the letters of reference marked thereon and being a part of this specification, in which the nature of my design is fully represented in the accompanying photographic illustration, in which—

Figure 1 is a perspective view of public urinal and water-closet, the walls of which are of corrugated sheet metal, and

Figure 2 is a horizontal section of the same.

I claim as my invention—

The design for a public urinal and water-closet, substantially as shown.

FREDRICK J. SMITH.
